UNITED STATES PATENT OFFICE

MELVILLE E. DUNKLEY, OF KALAMAZOO, MICHIGAN.

CANNING.

1,270,797.

Specification of Letters Patent

Patented July 2, 1918.

Application filed August 3, 1914. Serial No. 854,643.

To all whom it may concern:

Be it known that I, MELVILLE E. DUNKLEY, a citizen of the United States, residing at Kalamazoo, Michigan, have invented certain new and useful Improvements in Canning, of which the following is a specification.

This invention relates to improvements in canning.

10 The objects of this invention are:

First, to provide an improved canning process in which the material to be canned is cooked and sterilized, delivered into sterile cans in a sterile atmosphere, and sterile tops 15 are delivered to and sealed on said cans, all of said operations being conducted in a sterile atmosphere.

Second, to provide an improved canning process in which previously sterilized material is delivered into cans, tops are put on the cans and sealed thereon, all of said operations being carried on under live steam thus maintaining a sterile atmosphere and insuring complete and perfect sterilization.

25 Third, to provide an improved canning machine in which the material is sterilized, the cans to be filled are carried through a steam chest filled with live steam, the cans being sterilized and filled with the sterilized 30 material, provided with a sterilized top and the tops sealed on said cans within said steam chest whereby complete and perfect sterilization is insured.

Further objects, and objects relating to 35 details and economies of construction and operation will definitely appear from the detailed description to follow.

I accomplish the objects of my invention by the devices and means described in the 40 following specification. The invention is clearly defined and pointed out in the claims.

A machine by which I contemplate carrying out my invention is clearly illustrated in the accompanying drawing forming a 45 part of this specification, in which:

Figure I is a longitudinal sectional view thereof taken on the line 1—1 of Figs. II and III.

Fig. II is an enlarged top plan view of the 50 machine, the sterilizers and storage tank being omitted and the can filling device being shown in section on the line 2—2 of Fig. I, the front part of this machine being omitted for convenience in illustration.

Fig. III is an enlarged top plan view 55 showing the front part of the machine which is omitted from Fig. II.

In the drawing, similar reference characters refer to similar parts throughout the several views, and the sectional views are 60 taken looking in the direction of the little arrows at the ends of the section lines.

Considering the numbered parts of the drawing, 1, 1 are the sterilizers in which the material to be canned is cooked and sterilized before being delivered to the cans. 65 Each of these sterilizers is filled through a hopper 2 provided with a cut-off valve. The sterilizer is also provided with an exhaust head 4 provided with the usual baffle 70 plates to prevent the liquid contents from being blown out of said exhaust, and with the cut-off valve 5. The sterilizer is surrounded by a steam jacket 6 into which steam is introduced under pressure for the 75 purpose of heating the contents to the sterilizing point. Suitably journaled in the top of the sterilizer is the shaft 7 driven by a sprocket 9 suitably connected with a source of power and provided with a plurality of 80 paddles 8. These paddles are for agitating the material in the sterilizer and for keeping it constantly moving so that it will not stick to the walls and scorch. The sterilizer is provided with a gage 10, a pressure gage 11 85 and a thermometer 12. I provide as many of these sterilizers as is necessary to supply the canning machine properly and each of them is connected by means of a pipe 13 having a cut-off valve 14, with a storage tank 90 15, from which storage tank the sterilized material is delivered to the cans.

This storage tank is also provided with a steam jacket 16 into which cold water may be introduced to cool the contents or steam 95 if necessary to raise it to the desired point. A shaft 17 is suitably journaled in said tank and said shaft is provided with a plurality of paddles 18 for agitating the contents, the shaft 17 being driven by a sprocket 19 connected with a suitable source of power. The tank is also provided with a gage 20 and a thermometer 21. There is a suitable opening in the lower end of said tank which is connected with a measuring device 24 which 100 measures out and delivers to each can as it is brought beneath it, a quantity of material sufficient to fill the same.

I provide a steam chest 23 of approximately the height of the cans, said steam chest 23 being supported upon standards 25, 25. At both ends of said steam chest are 5 provided supports 26, 26, which carry the sprocket wheels 27, 27, carrying the endless chain conveyer 28, which is provided at suitable intervals with upstanding lugs 29. At the rear end of the machine there is provided, upon the same shaft that carries the 10 sprocket wheel 27, a stop wheel 30 which is actuated by a stop mechanism 31 carried by the shaft 40 so as to drive the said sprocket wheel 28 with an intermittent rotary movement.

At the bottom of the steam chest 23 are ways 32, 32 upon which the bottom of the can 33 rests as it is carried through the steam chest. The conveyer 28 runs between 20 said ways and the upstanding lugs 29 project so as to catch the bottom of each of the cans to carry them through the steam chest.

Steam is introduced into the steam chest by means of a steam pipe 34 provided with 25 a plurality of branches 35 so spaced that, in the operation of the machine, as the cans are carried forward with an intermittent movement, a can is stopped directly beneath each of the branches 35 so the steam under 30 high pressure may be injected directly into the can to thoroughly sterilize the same. I also provide a steam pipe 36 provided with a plurality of branches 37 toward the rear end of the steam chest so that steam under high pressure is injected upon the cans as 35 they are about to leave the steam chest. This insures the steam chest being filled with live steam under pressure throughout its entire length so that as the cans are carried 40 through said steam chest they are enveloped by live steam. A plurality of drain pipes 38, 38 are provided in the bottom of said steam chest to carry off the condensed moisture.

45 Power is applied to the machine by means of the driving pulley 39 which drives the shaft 40 and the longitudinally extending shaft 42 is driven by a bevel gear connection 41 with the shaft 40. The longitudinally 50 extending shaft 44 is also suitably connected so as to rotate with the shaft 42. 24 is the measuring mechanism which at predetermined intervals measures a quantity of material from the storage tank sufficient to 55 fill one of the cans and delivers it to the can which is brought into line with the discharge opening of said measuring device. This mechanism is operated by means of the connections 43 and 45 with the shafts 60 42 and 44 respectively, and said mechanism is so timed that as the cans are brought forward with an intermittent movement and each can comes to rest beneath the discharge opening of the measuring mechanism 24, 65 this mechanism will be operated to deliver

the required quantity of sterilized material into the sterilized can which has been brought into position to receive it.

From the measuring and delivering mechanism the cans are carried forward by the intermittent movement of the chain 28 to the top feeding mechanism 46. The tops which are supplied to the cans are carried by the cylinders 47, 47, which are mounted upon the rotatable turn table 49, the tops being delivered by the mechanism from one of said cylinders while the other cylinder is being filled with fresh tops by an operator. Steam is introduced into these cylinders 47 by means of a steam pipe 48 so that the tops 80 which are to be placed upon the cans are thoroughly sterilized before they are delivered. This delivery mechanism, as each can is brought beneath it, separates one top from the supply of tops and deposits it upon 85 the can. This operation is conducted entirely in the steam chest so that the can and top are entirely enveloped by live steam.

From said top feeding mechanism the cans are carried forward by the intermittent 90 movement of the chain to the sealing mechanism 50, which at the proper interval fastens and hermetically seals on said cans the sterilized tops previously placed thereon. This operation is also conducted in the presence of live steam and under sterile conditions. From this mechanism the cans are carried beneath the steam pipe 37, 37 and discharged from the rear end of the machine.

I have not particularly described the measuring mechanism 24, the top feeding mechanism 46, nor the sealing mechanism 50. Mechanisms of this type are all old and well known in the art and any one of these old and well known mechanisms suited to this purpose may be used in this connection. The particular mechanism which is used to accomplish these operations forms no part of my invention.

In carrying out my invention the material to be canned is introduced into the sterilizer 1 through the hopper 2. Steam is introduced into the steam jacket 6, the pressure and temperature at which said steam is introduced varying according to the sterilizing temperature desired, depending upon the material which is being sterilized. It will be apparent that other methods of applying heat, such as preheated air, may be used in place of steam. The temperature is maintained until sterilization is accomplished. The revolving shaft 7 provided with the paddles 8 violently agitates the contents so as to insure uniform heating. This also keeps the material from sticking to the walls of the sterilizer and scorching.

While I have shown and described steam jacketed sterilizers, nevertheless for some kinds of work the introduction of live steam 130

directly into the material would be desirable, and I consider such a practice as within the spirit of my invention.

After the temperature has been kept at 5 the sterilizing point for the required length of time, the valve 5 in the exhaust head is opened so as to lower the pressure and allow the temperature to drop. The exhaust head 4 is provided with baffle plates of the usual 10 construction to prevent the liquid contents from being blown out through the exhaust head when the valve 5 is opened. The valve 14 in the discharge pipe 13 is then opened and the contents of the sterilizer discharged 15 into the storage tank 15. The jacket 16 of the storage tank 15 is provided so that cold water or steam may be introduced for controlling the temperature of the sterilized material contained therein. This tank is 20 also provided with a revolving shaft carrying paddles to thoroughly agitate the material.

In the lower end of the storage tank there is provided the discharge opening 22 leading 25 into a measuring and feeding device 24. The steam chest 23 is suitably supported below said hopper, and chain 28 carries the cans to be filled through said steam chest, the stop movement giving the chain an intermittent forward movement. The cans are placed upon the ways 32 and the lugs 29 on the chain engage said cans to carry them forward through the steam chest.

As the cans are carried forward in the 35 steam chest they are brought to rest beneath the steam pipes 35 which are supplied with steam under pressure and at a sterilizing temperature. This steam is discharged in jets directly into the interior of the cans so 40 that all the air in the cans is forced out and they are completely filled with live steam. This completely sterilizes the cans and also fills this end of the steam chest with live steam.

45 Passing from the steam jets the empty cans are brought to rest beneath the measuring device 24 which measures and delivers to the sterilized cans from the storage tank a quantity of sterilized material sufficient to 50 fill the cans. These cans have been previously sterilized by the steam jets 35 and the steam chest in which they are disposed is filled with live steam.

From the measuring device, the cans are 55 carried forward by the chain to the top feeding device 46 by means of which, as each can is brought to rest, a top is separated from the supply of tops and is deposited upon the can. These tops are stored in cylinders 47 and steam is admitted under pressure and at a sterilizing temperature to these cylinders so that the tops are thoroughly sterilized before they are deposited upon the cans. Some of this steam also finds its way 60 into the steam chest 23 so that this pipe also

serves as an additional means for supplying live steam to the steam chest.

From the top feeding mechanism the cans are carried forward by the intermittent movement of the chain to the sealing device 70 50 which at proper intervals operates to fasten and hermetically seal the sterilized tops upon the sterilized cans and contents. This operation is also conducted within the steam chest in the presence of live steam. 75 Beyond the sealing device I provide a steam pipe 36 through which steam is supplied under pressure, said steam pipe being provided with a plurality of branches 37 discharging into the steam chest. By means of 80 these steam pipes I insure the presence of live steam throughout the entire length of the steam chest so that the cans during their entire progress through the latter are enveloped and surrounded by live steam and are 85 in a sterile atmosphere. The introduction of this live steam displaces and keeps out the non-sterile air. At the rear end of the steam chest the cans are removed from the machine. 90

95 By means of my improved process of canning the entire operation of cooking and sterilizing the material to be canned, delivering said material to the sterilized cans, placing sterilized tops upon said cans and sealing said tops is carried on under live steam and is entirely automatic. In view of the fact that this operation is carried on under live steam it is absolutely impossible for any living germ to come in contact with the material and in view of the fact that it is thoroughly sterilized in this manner it is not necessary to sterilize the material to be canned after it is sealed in the can, as has been customary heretofore. By means of 100 this improved process the quality of the product is greatly improved and the time necessary for carrying it out is greatly lessened. 105

I am aware that the particular embodiment which I have here shown is susceptible of considerable variation without departing from the spirit of my invention and, hence, I do not wish to be restricted to the same. I have found, however, that this particular form is to be preferred, and, therefore, I desire to claim the same specifically as well as broadly as indicated by my appended claims. 110

115 Having thus described my invention, what I claim as new and desire to secure by Letters Patent is:

1. In a machine of the class described, the combination of suitable base members, a steam chest supported thereon, means for 120 supplying jets of steam to said chest, a chain having an intermittent motion carrying the cans to be filled through said steam chest, said cans being brought to rest beneath said steam jets, an opening in said steam chest 125 130

beneath which said cans come to rest, a filling device discharging a measured quantity of sterile material through said opening at predetermined intervals, a sterilizer supplying said filling device, a second opening in said steam chest beneath which said cans come to rest, a mechanism for feeding tops through said opening to the cans, a third opening in the steam chest beneath which 10 said cans come to rest, and a mechanism for fastening said tops to the cans, said steam chest being filled with live steam throughout its length, all coacting substantially as described for the purpose specified.

15 2. In a structure of the class described, the combination with a plurality of sterilizers, a storage tank connected with said sterilizers, a steam chest suitably supported beneath said tank, means carrying the cans to be filled through said steam chest, a steam pipe in the front end of said steam chest supplying a plurality of steam jets thereto, an opening in said steam chest, means delivering material from said tank through said 20 opening into the cans to be filled, a second opening in said steam chest, means for sterilizing the tops for said cans and delivering said tops through said opening to the cans to be filled, a third opening in the steam 25 chest, and means operating through said opening to seal the tops to the filled cans, and a second steam pipe supplying a plurality of jets to said steam chest, all coacting 30

substantially as described for the purpose specified.

35

3. In a structure of the class described, the combination with a plurality of sterilizers, a storage tank connected with said sterilizers, a steam chest suitably supported beneath said tank, means carrying the cans to be filled through said steam chest, means supplying a plurality of steam jets thereto, automatic means delivering from said tank into the cans to be filled, means for sterilizing the tops for said cans and delivering 40 said tops to the cans to be filled, all coacting substantially as described for the purpose specified.

40

4. In a structure of the class described, the combination with a sterilizer, a steam chest 45 suitably supported beneath said sterilizer, means carrying the cans to be filled through said steam chest, means supplying a plurality of steam jets thereto, means delivering from said sterilizer into the cans to be filled, means for sterilizing the tops for said cans and automatically delivering said tops to the cans to be filled, all coacting substantially as 50 described for the purpose specified.

50

In witness whereof, I have hereunto set 55 my hand and seal in the presence of two witnesses.

55
